Application May 4, 1937, Serial No. 140,598
 In Great Britain August 6, 1936

8 Claims. (Cl. 179—100.3)

This invention relates to light valves and more particularly to improvements in the construction and operation of such devices employed in photographic sound recording systems.

It has been found that for certain purposes, advantages may be gained by utilizing various forms of double track sound records. In one of the sound records of this double track type, known as a push-pull sound record, the two half waves of the sound wave are recorded 180 degrees out of phase in the two separate adjacent tracks. Another sound record of the double track type is known as a stereophonic sound record in which the separate adjacent tracks represent the same sound waves as recorded from different positions with respect to a single sound source. A further record of this type is known as the split frequency record in which each track is a record of the sound frequencies within a certain frequency band included in the recorded sound.

For studio recording of variable density double track records by means of light valves of the well-known type disclosed in United States Patent 1,638,555, August 9, 1927, to E. C. Wente, two light valves are required, which involves the use of separate light sources and separate optical systems to bring the two modulated light beams to a single recording film.

It has been recognized for some time that substantial economy and increased operating efficiency would be made possible if there could be provided a recording system comprising a single light source, a single optical system and a single unit light valve incorporating separate light modulating units in a single magnet structure. It has been found extremely difficult, however, to provide a single unit light valve having two separate light modulating systems vibrating in a single magnet structure and at the same time maintain the requisite operating efficiency and preciseness of adjustment of the various elements of the vibrating system of the light valve.

It is the object of this invention to provide a single light valve structure incorporating a plurality of vibrating systems adjustably mounted for efficient operation in the magnetic field of the single light valve structure.

A feature of the invention lies in the provision of novel adjustable supporting means for the separate light valve ribbons and in the novel arrangement of these supporting means with respect to the magnet pole-pieces to permit accurate tension and spacing adjustment of each ribbon with respect to the pole-pieces.

Another feature of the invention lies in the

provision of means fixedly incorporated in the light valve structure to extend into the region of the aperture formed by the light valve ribbons for deflecting modulated light rays to the exterior of the light valve structure for monitoring purposes.

A further feature of the invention lies in the provision of optical means disposed in the paths of the light beams emerging from the pole-piece apertures for transversely aligning the light beams on the recording film and in the provision of a novel support for said optical means which may be removably mounted in operating position in one of the pole-pieces.

In the drawings:

Fig. 1 is a diagram showing the essential elements of a sound film recording optical system using a light valve as the modulating means;

Fig. 2 is a top plan view of the light valve plate on which one pole-piece, ribbons and ribbon supporting means are mounted as a unit therewith;

Fig. 3 is a side view of the plate shown in Fig. 2;

Fig. 4 is a bottom plan view of the pole-piece supporting plate showing the plate face opposite that shown in Fig. 2;

Fig. 5 is an enlarged section taken through line 5—5 of Fig. 4;

Fig. 6 is a section taken through line 6—6 of Fig. 7;

Fig. 7 is a plan view of the pole-pieces and ribbon support mounted on the supporting plate;

Fig. 7A shows the support for a second light valve pole-piece;

Fig. 8 shows details of the removable holder for the aligning prism of the optical system;

Fig. 9 is a schematic showing of the monitoring means of the invention;

Fig. 10 is a plan view, partly in section, of the recording optical system showing the manner in which the optical deflecting prisms produce transverse alignment of separate recording light beams on the recording film;

Fig. 11 is a side elevation of the optical system shown in Fig. 10; and

Fig. 12 is an enlarged perspective view, partly in section of the ribbon support and pole-piece.

Referring to Fig. 1, the recording system shown therein includes a recording machine 1 in which is housed a film driving drum 2 for driving a photographic film F. Light rays of constant intensity from a light source 3 are projected by means of condensing lens system 4 to focus at a point between pole-pieces 5 and 6 of a light valve 7. The light rays emerging from the light valve 7 are projected by means of an objective lens sys-

tem 8 to the film F on drum 2. The light valve 7 includes a member 9 of magnetic material surrounded by an electromagnet 10 for creating a magnetic field at the light valve pole-pieces 5 and 6. A rectangular plate 11 is removably secured to the main body portion of the light valve 7 by means of machine screws 12 and 13. Binding posts 14, 15 and 16 are secured to plate 11 and provide means whereby an input circuit or 10 circuits may be connected to the light modulating elements of the light valve 7 through wires 17 (Fig. 4).

Plate 11 is apertured as at 18 to allow passage of the modulated light rays to the objective lens 15 8. One pole-piece 6 and supporting means for the light valve ribbons are secured to plate 11 adjacent the aperture 18 in a manner to be described.

A member 19 is secured to plate 11 by means 20 of machine screws 20 and 21 (Figs. 2 and 5). Member 19 is provided with an aperture 22 extending into the area of aperture 18 in plate 11. The pole-piece 6 is divided into two sections 25 (horizontally as seen in Fig. 7) to facilitate assembly and is secured to the member 19 by means of machine screws 24 and 25 (Fig. 7).

The pole-piece 6 is provided with two offset recording apertures 26 and 27. An aperture 28 30 in line with recording aperture 26 and aperture 29 in line with recording aperture 27 constitute what will be called "monitoring apertures", the purpose of which will be explained further in this specification.

In Figs. 3, 4 and 7A the member 30 constitutes a carrier for the second light valve pole-piece 5. This pole-piece 5 is divided into two sections to facilitate assembly and is secured to member 30 by means of machine screws 32 and 33. This member 30 has an aperture 34 in line with offset recording apertures 35 and 36 of 35 pole-piece 5. Monitoring apertures 37 and 38 are provided in pole-piece 5 to be in alignment with monitoring apertures 28 and 29 of pole-piece 6, respectively, when the light valve 7 is 40 assembled. While applicant discloses separate recording apertures and monitoring apertures, such as 26 and 28 respectively, a single aperture may be provided of such a length as to include the areas occupied by the two separate apertures. Member 30 has secured thereto, by machine 45 screws 42 and 43, members 40 and 41 (Fig. 5) which are provided with apertures 44 and 45 to allow passage of monitoring light beams to the exterior of the pole-piece structure at right angles to the recording light beam.

The novel means provided for directly monitoring the operation of the vibrating systems of the light valve comprises, in addition to the aligned pole-piece monitoring apertures 28-37 60 and 29-38, members 46 and 47 of light transmitting material, preferably quartz. Each of these members has one end extending into the area of the monitoring apertures 28 and 29, respectively, (Fig. 12). The end extending into 65 the area of the aperture is beveled as at 48 and is provided on this beveled portion with an inner reflecting surface to deflect light rays coming through the apertures along the members 46 and 47. Each of the rods 46, 47 is covered 70 throughout its length, except for the area immediately in front of the monitoring aperture, with a protective coating of opaque material 50, which, in this disclosure, is a thin metallic covering. As shown schematically in Fig. 9, the 75 light rays emerging from rods 46 and 47 are

projected to the exterior of the pole-piece structure and are deflected thereafter by suitable optical prisms 51 and lenses 52 to photosensitive devices 53 connected in a suitable reproducing circuit. This novel monitoring feature may be applied to a single string and to a two string light valve having a single recording aperture by employing one only of the light transmitting rods in the pole-piece structure of the single string or two string light valve.

The constant intensity light beam from light source 3 which passes through aligned recording apertures 35 and 26 in opposed pole-pieces 5 and 6, respectively, is modulated by means of vibrating ribbons 55 and 56, while the constant intensity light beam projected through aligned apertures 36 and 37 in opposed pole-pieces 5 and 6, respectively, is modulated by means of vibrating ribbons 58 and 59. It will be noted that the four vibrating ribbons 55, 56, 58 and 20 59 are mounted alternately in separate, but parallel planes.

Referring particularly to Figs. 6, 7 and 12, the novel adjustable means for anchoring the ribbon ends comprises a plurality of supporting members 60, 61, 62, 63, 64, 65, 66 and 67. Fig. 12 shows in detail the manner in which these supports are mounted in member 19. Supports 60, 61, 64 and 65 employed to support ribbons 58 and 59 are shown in detail in the figure.

Member 19 is provided on each side of the pole-piece 6 with internal side flanges 68 and 69. The entire inner surface of member 19 in contact with the ribbon supporting members is covered with an insulating material 70. As each of the ribbon supporting members is identical and each is supported in the member 19 in identical manner, the description of one supporting member 60 and the manner in which it is mounted in member 19 will suffice.

Referring particularly to Figs. 6 and 12, opposite ends of a rigid bar 71, composed of some suitable insulating material, engage the under side of flanges 68 and 69. A machine screw 72 extending through member 71 engages a threaded hole in the bottom of member 60. Member 60 rests on flange 68 and on central supporting bar 73 of some suitable insulating material. It is evident from this disclosure that tightening of screw 72 will anchor member 60 rigidly in place 50 in the member 19. Each of the ribbon supports 61 to 67, inclusive, are mounted in the manner described above in connection with support 60 and the supports are electrically insulated from each other and from the mounting member 19.

As shown particularly in Fig. 7, numerals 75 75 and 76 designate spacing blocks of solid construction which are rigidly mounted in the member 19 in the same manner as the ribbon supports.

In Fig. 12 of the drawings applicant discloses 60 the ribbon supports 60, 61, 64 and 65 for supporting vibrating ribbons 58 and 59 and also the means provided for spacing and tension adjustment of these ribbons. Supports 62, 63 and 67 for ribbons 55 and 56 are adjustable as to tension 65 and spacing in an identical manner and for the sake of clearance applicant has eliminated the latter supports from the disclosures in Fig. 12.

It will be seen that ribbon support 64 comprises two standards 114 and 115 rising from a 70 common base. Standard 114 is substantially rigid. The ribbon suspending standard 115 is provided with an aperture 80. The provision of aperture 80 in standard 115 and the fact that the two standards are separated throughout the 75

greater portion of this height by a cut-out 82 makes the ribbon supporting extremity of support 115 slightly flexible.

Spacing adjustment of one end of ribbon 59 is obtained in the following manner. Standard 114 has a threaded hole therethrough into which a machine screw 83 is threaded. One end of this machine screw 83 bears against a side of standard 115. Due to the flexibility of the ribbon suspending extremity of standard 115, adjustment of screw 83 against this standard produces sufficient movement thereof in a direction at right angles to the length of the ribbon 59 to provide the necessary lateral spacing adjustment 15 of this ribbon with respect to the recording aperture 21 in pole-piece 6 and with respect to ribbon 58. Standard 79 of support 60 is adjustable in the same manner by means of a machine screw 81. Supports 61 and 65 are each adjustable in a manner similar to that described in connection with supports 60 and 64 to provide spacing adjustment for ribbon 58.

Means for adjusting the tension of ribbon 59 is provided at support 60 for this ribbon. Figs. 25 7 and 12 disclose that the tension of ribbon 59 is adjusted by means of a machine screw 84 threaded through standard 79 of support 60 to bear against the adjacent rigidly mounted spacing block 75 (Fig. 7). Movement of machine screw 84 against member 75 will produce movement of standard 79 in the direction of the length of ribbon 59 to produce the necessary tension therein.

The tension of ribbon 58 is adjusted by a movement of standard 86 of support 61 in the following manner. Standard 85 has secured thereto by means of a machine screw 87, a rigid member 88 provided at its free end with a machine screw 89 which passes through member 40 88 and into a threaded hole in standard 86 of support 61. As standard 85 is wider than standard 86 there is sufficient space between member 88 and standard 86 to permit movement of the standard toward or away from this member. 45 Rotation of machine screw 89 in a clockwise direction produces sufficient movement of standard 86 of support 61 to produce a tension in ribbon 58. The tensioning means for ribbons 55 and 56 are identical with those of 59 and 58 respectively and are associated with the end ribbon supports 66 and 67 located at the opposite side of pole-piece 6 (Fig. 7).

Ribbon 59 is anchored to standard 79 of support 60 by means of a clamping bar 90 which is 55 provided with two machine screws 91 extending into threaded holes in standard 79. The opposite end of ribbon 59 is anchored to standard 115 of support 64 by means of a clamp 92, provided with machine screws 93 extending into 60 threaded holes in standard 115. Ribbons 55, 56 and 58 are anchored to their respective supports by clamps similar to clamps 90 and 92. The width of the ribbon engaging projection of the clamps 90 and 92 is slightly smaller than the 65 width of the vibrating ribbon clamped thereby to insure against buckling of the vibrating edges of ribbon 59.

The vibrating ribbons 55, 56, 58 and 59 are supplied with sound modulated electric currents 70 from a recording microphone circuit connected to binding posts 14 and 15 mounted on plate 11. Wires 17 carry these microphonic currents to electrically conductive pins embedded in a strip of insulating material 95 secured to plate 11. 75 Separate insulated wires such as 96 (Fig. 6) con-

nect each of these pins to the separate machine screws 72 associated with each of the members 64 to 67 inclusive supporting one end of each of ribbons 55, 56, 58 and 59. The supports associated with the other end of each of ribbons 55, 56, 58 and 59 are each electrically connected through an associated machine screw 72 and wire 96 to one of the electrically conductive pins embedded in a strip of insulating material 97 secured to plate 11. Ribbons 55 and 56 are electrically connected to form a loop by means of a conductive connection 98, while ribbons 58 and 59 are electrically connected to form a separate loop by means of conductive connection 99.

In this disclosure the ribbons 55, 56, 58 and 59 are connected electrically, as shown schematically in Fig. 9, to produce a push-pull sound record. The sound modulated currents are conducted through the pair of conductors 58 and 59 forming one vibrating system in a direction opposite to the direction of the same currents through the pair of conductors 55 and 56 forming the other vibrating system. It is quite apparent, however, that the two vibrating systems may be connected, after minor modifications, to separate electrical circuits for production of either stereophonic or split frequency sound records. Also, noise reduction currents may be connected to the vibrating systems in an appropriate manner and in the present disclosure the binding post 16 is supplied for this purpose.

It can readily be seen that due to the offset of the recording apertures 26 and 27 in pole-piece 6, the separate modulated light beams will be projected to and recorded on film F in separate tracks in offset relation, that is, the two simultaneously recorded records will not be in transverse alignment on the recording film. In practically all sound film reproducing equipment a single transverse slit is employed to limit the area of the reproducing light beam to the film sound record. Therefore, double track sound records of any of the types discussed above and wherein the two tracks are displaced relative to each other longitudinally of the film could not be reproduced in standard theatre reproducing apparatus.

To avoid the necessity of modifying existing sound reproducing apparatus, applicant provides means whereby transverse alignment of the offset modulated light beams from the recording light valve pole-pieces is produced in the recording optical system between the light valve and film.

Referring particularly to Figs. 10 and 11, the modulated light beam emerging from aperture 21 in pole-piece 6 is intercepted by light transmitting and refracting member 100 so disposed that the light beam is deflected downward. The modulated light rays emerging from aperture 26 in pole-piece 6 are intercepted by light transmitting and refracting element 101 so disposed that the modulated light beam is deflected upward. The angle at which these refracting elements are disposed in the optical system is so chosen that the two beams will be in transverse alignment at the optical axis of the recording optical system and will be recorded on film F in transverse alignment side by side.

Referring to Figs. 5 and 8, applicant discloses a novel holder for the refractor elements 100 and 101. This holder comprises an element having side walls 102 and 103 joined by apertured transverse portions 104, 105 and 106. Re-

fractor plates 100 and 101 have their ends mounted in the portions 104, 105 and 106 as shown in Fig. 8. These refractors may be adjusted in their mounting and maintained in adjustment by the application at the mountings of a small amount of cement or other suitable sealing material. In the event readjustment is necessary at any time, this seal may be easily broken and reformed after readjustment has been made.

The holder may be removably inserted into member 19 with the refractor elements adjacent the recording apertures in pole-piece 6. The side walls 102, 103 are made slightly flexible in the manner shown and are each provided with a projection 107. Other portions of the side walls are flanged as at 108. The knurled portions of side walls 102 and 103 may be taken between the thumb and forefinger and sufficient pressure exerted thereon to permit passage of the holder into aperture 22 in member 19 until flange 108 engages a face of member 19. The holder is held in member 19 by means of the projection 107, which extends into a recess 109 in the inner side wall of member 19.

It will be noted that one end of each of the ribbons 55 and 59 is supported adjacent the pole-piece 6 by supports 63 and 64, respectively. As the amplitude of movement of these ribbons depends both on the strength of the constant magnetic field and the current through the ribbons, the portion of the ribbon between the pole faces is subject to the maximum and therefore greater moving force than the end portions of the ribbons not included between the pole faces. It is therefore evident that one end of each of the ribbons 55 and 59 clamped to supports 63 and 64, respectively, are subjected to a greater shearing strain at the point of clamping than the ribbons clamped by the remaining supports further removed from the pole-pieces.

To reduce the possibility of ribbon shearing at the supports 63 and 64, the strength of magnetic field at certain portions of the pole faces of pole-pieces 5 and 6 is reduced by removing small portions thereof directly adjacent supports 63 and 64 as at 110 and 111 on pole-piece 5 (Fig. 7A) and at 112 and 113 on pole-piece 6 (Fig. 7).

50. What I claim is:

1. The combination in a light valve having oppositely disposed pole-pieces provided with aligned apertures and a pair of conducting elements arranged between said pole-pieces to form a light transmitting slot, of means for monitoring the movements of said conducting elements, said means comprising a light transmitting element mounted in one of said pole-pieces with one end extending into a portion of the physical area of the aperture therein, and light sensitive means included in a reproducing circuit disposed in the path of light emitted from the opposite end of said element.

2. The combination in a light valve having oppositely disposed pole-pieces provided with aligned rectangular apertures and a plurality of conducting elements arranged between said pole-pieces for movement in front of the apertures therein, of means for monitoring the movements of said conducting elements comprising a light transmitting element mounted in one of said pole-pieces at an angle to the longer axis of the aperture therein with one end thereof extending into a portion of the physical area of the aperture in said pole-piece, the other end of said

element extending to the exterior of said pole-piece structure.

3. A light valve comprising a pair of oppositely disposed pole-pieces each having a pair of light transmitting apertures, a conducting element movable in front of the apertures in said pole-pieces to vary the amount of light projected therethrough, and means for utilizing the light beam projected through one of said apertures for monitoring purposes.

4. The combination in a light valve having oppositely disposed pole-pieces provided with aligned apertures and a plurality of movable conducting elements disposed between said pole-pieces, of light transmitting means mounted in one of said pole-pieces, said means having one end thereof beveled and provided with a reflecting surface extending into a portion of the physical area of the aperture in said pole-piece and the other end thereof extending through the exterior of the pole-piece structure whereby a portion of the light beam modulated by said conducting element is made available for monitoring purposes.

5. A sound recording system comprising means to project a beam of light to a record surface and means to modulate said beam in accordance with the sounds to be recorded, said means comprising a light valve having oppositely disposed pole-pieces provided with a plurality of aligned apertures, a plurality of conducting elements movable between said pole-pieces to vary the amount of light projected through the plurality of apertures therein, means for monitoring the movement of said conducting elements, said means comprising a plurality of light transmitting elements mounted in one of said pole-pieces in non-interfering relation with said conducting elements, each light transmitting element having one end thereof extending into the physical area of certain of said apertures with the other end thereof extending to the outer boundary of the pole-piece structure, and a light sensitive means disposed in the path of light from each of said light transmitting elements.

6. The combination in a recording optical system having means to project a beam of light to a recording film, of means to modulate said light beam in accordance with sounds to be recorded, said means comprising a light valve having oppositely disposed pole-pieces each provided with a pair of aligned apertures displaced in opposite directions with respect to the optical axis of the recording system, conducting elements disposed between said pole-pieces and movable in response to sound currents to vary the amount of light passing through each of the aligned apertures in said pole-pieces, and optical means intercepting each of the modulated light beams from said pole-pieces for deflecting each beam toward the optical axis of the recording system whereby the pair of modulated beams will be recorded on said film in transverse alignment.

7. A light valve comprising a pair of oppositely disposed pole-pieces each having a pair of light transmitting apertures, a conducting element movable in front of the apertures in said pole-pieces to vary the amount of light projected therethrough, and means mounted in one of said light valve pole-pieces for deflecting the modulated light beam projected through one of the apertures therein whereby said deflected beam may be utilized for monitoring purposes.

8. The combination in a recording optical system having means to project a beam of light to

a recording film, of a member disposed in said optical system provided with a pair of offset apertures disposed above and below a horizontal plane including the optical axis of said system, means to modulate the light passing through the apertures in said member in accordance with sounds to be recorded, and means disposed in

said optical system for deflecting the modulated beams projected through the apertures in said member in opposite directions to produce horizontal alignment of said beams in the plane including the optical axis of said system at the recording surface of said film.

JOHN G. FRAYNE.
